UNITED STATES PATENT OFFICE

JOHN A. FLOOD, OF MINNEAPOLIS, MINNESOTA

WEB HOLDING MACHINE

Application filed June 25, 1925. Serial No. 39,629.

My invention relates to web stretching machines wherein it is desired to provide a machine adapted to hold a series of webbing rolls in the base of the same, the ends of which extend out to the holding mechanism 5 in a manner so that they can be attached to the various articles and secured thereto and then stretched as may be desired so as to draw the webbing taut over the surface of 10 the articles to which it is being attached.

A feature of my invention resides in a web stretching mechanism wherein the detail of construction is simple and inexpensive, yet effective to hold each of the strips 15 of webbing in place and so that a series of strips can be held and adjusted to the article, such as a piece of furniture, when it is desired to attach the webbing to the same. It is quite important that the webbing be properly attached to the article and it is essential 20 that the web stretching machine be portable so that it can be moved from place to place and thus permit the adjusting of the webbing, in fitting the same to articles in 25 different places in the factory where they are being made and finished.

It is an object of my invention to provide a web strap stretcher which is adapted to stretch all of the pieces of webbing which 30 extend in approximate parallel relation to each other in a uniform manner. This is important so as to provide the proper bottom for the chair or other piece of furniture to which the webbing is adapted to be attached. My web stretcher is adapted for 35 use in modern upholstery manufacturing establishments where webbing is constantly used and the simple, effective operation of my machine provides a device which permits 40 a saving of time and labor to a very marked extent.

The invention includes a web holding device and stretcher which is adjustable so that it can be connected with various articles 45 of furniture and of a portable nature so that it can be moved about the upholstery manufacturing plant to provide a very convenient web holding machine and to permit the operator to readily adjust the same 50 to the article on which the webbing is to

be attached. The series of webbing strips can be individually drawn taut to approximately the same degree, and then by a unit operating lever the webbing drawn taut to stretch the same while a suitable locking dog 55 on the end of the mechanism is adapted to hold the webbing stretched and against backward movement until it has been secured to the piece of furniture on both ends. The webbing is then severed or cut off uniformly 60 at the edge of the piece of furniture and the machine is then ready to be adjusted to the new piece of furniture so as to attach the webbing strips across the bottom of the 65 same.

It is also an object of my invention to provide a series of gripping dogs for engaging the webbing in a manner so as not to tear or mar the same, yet holding the webbing so tightly that it can be stretched 70 to the desired degree to draw the same tight over the bottom of the furniture.

It is also a feature of my invention to provide for holding the rolls loose and free so that they can be inserted quickly into 75 the machine without having any complicating holding or connecting means for the same. The compartment for holding the rolls is simple, yet the rolls are held side by side so that several strips of webbing can 80 be operated by the machine at one time.

My invention includes an adjusting means so that the height of the web table can be adjusted to the article to which the webbing 85 is to be attached. This is quite important as it permits the device to be adjusted readily to the desired height and thus allows the operator to work more efficiently.

These, together with other features, will be more fully set forth in the following specification and claims:

In the drawings:

Figure 1 is a perspective view of my web stretcher in operation.

Figure 2 is a plan view of the same.

Figure 3 is a side sectional elevation of my web stretching machine.

Figure 4 is a side sectional elevation on the line 4-4 of Figure 2.

Figure 5 is an end view on the line 5-5 of

Figure 2, showing the parts in enlarged formation.

Figure 6 is a detail of a portion, the upper portion, of the webbing machine similar to 5 the section on the line 4—4 of Figure 2, showing the parts in a different position.

Figure 7 is an edge view of one of the dogs of the machine for gripping the webbing.

10 Figure 8 is a side view of the dog illustrating the formation of the same.

Figure 9 is a sectional detail of a portion of my machine, taken on the line 9—9 of Figure 4.

15 In the drawings the web holding machine and stretcher A is formed with a base B which is provided with castors 10 so that the same can be moved about from place to place. The base B supports the body frame 20 C extending upward from the same with side walls 11 and 12.

The base B is provided with a webbing roll receptacle 13 into which the rolls 14 of webbing are loosely and freely held so that 25

the webbing strips 15 can be threaded through the opening 16 up to the gripping and holding mechanism E on the upper part of the frame C. The webbing rolls 14 are held in a series in the compartment 13 and 30 the opening 16 is in form of a narrow slot at the forward end and at the upper side or edge of the compartment 13 so that the strips of webbing 15 can be readily and freely passed through the same up to the gripping and holding mechanism E. This 35 holds the rolls of webbing in a manner so that they can be easily replaced at any time, or removed, without any necessity of having them centered or held on a shaft and 40 without taking any of the machine apart.

The web gripping mechanism E is mounted upon the top of the frame C at the upper end of the sides 11 and 12. This 45 mechanism E consists of a horizontal shaft 18 which is provided with a longitudinally extending and projecting key 19, the shaft 18 is adapted to carry a series of gripping dogs 20 which are positioned adjacent each other on the shaft and are freely held there- 50 on being provided with a key slot 21 in each dog. The key slot 21 is slightly larger than the key 19 so as to permit the dogs to rotate freely the distance of the width of the key slot 21. This permits the dogs 20 to prop- 55 erly adjust themselves in relation to the webbing strips 16 which extend over the gripping dogs 20 in a manner so as to be engaged by the same.

60 The shaft 18 is supported by upwardly projecting side flanges 22 to support the same above the gripping table portion 23. The table 23 is positioned directly below the free end of the gripping dogs 20 and is pro- 65 vided with a serrated surface 24 positioned directly beneath the dogs 20 and the dogs 20

are also provided with a serrated surface 25 on the co-surface of the free end of the same which co-acts with the gripping surface 24 to grip the strips of webbing 15 by the dogs 20 and the table 23, when it is desired to 70 draw the webbing taut in the operation of my machine.

The table 23 is formed with a forwardly extending arcuate portion 26 which forms a cylindrical like surface extending between 75 the sides 11 and 12 of the machine A. On one end of the cylindrical portion 26 of the table 23 I provide a locking notch 27 into which the tooth 28 of the lever 29 engages to hold the table with its cylindrical or arcuate surface stationary. A notch 27 is formed in the plate 30 which is rigidly attached to the end of the table 23 and is formed with a series of teeth 31 which are adapted to be engaged by the serrated edge of the tooth 28 when the arm 29 is lifted out of the locking notch 27 and the table 23 is rotated to hold the table in a set position by the engagement of the arm 29 with the teeth 31.

80 The plate 30 is bolted to the end of the table 23 by means of the bolts 34 extending from the inside of one end of the table 23 so as to rigidly attach the same thereto, and a plate member 35 is interposed between the plate 30 and the end of the table 23 which 85 extends upwardly to form the end bearing 90 for the shaft 18. Projecting from the ends of the table 23 I provide gudgeons 36 which engage in the sides 11 and 12 at the frame to 95 pivotally hold the table 23 in relation to the frame C of my machine A. The plates 35 are connected to and extend upward from each end of the table 23 as illustrated in Figures 4 and 9 of the drawings.

The table and cylindrical member 23 have 100 secured to the opposite end from the plate 30 a handle 37 which is provided with a plate portion 38 which is bolted to the end of the member 23 by similar bolts 34 which hold the plate 35 at this end of the table member 23, as illustrated in Figure 9.

A handle 37 is adapted to operate the rotative movement of the table member 23 and as the plate members 35 support the shaft 18 connected to the table member 23 when the same is rotated by the handle 37, the series of dogs 20 are carried in a rotative manner on the gudgeons 36 to permit the rotating movement of the dogs 20 together with the connecting parts collectively.

110 The shaft 18 carries a short handle 40 on the inside of the plate 35 which is rigidly connected or keyed to the shaft 18 and which is adapted to form a releasing handle which 115 when operated lifts the dogs 20 out of engaging position by rotating the shaft 18 in a backward direction. This handle 40 provides 120 means so that if the operator of my web stretching machine desired to raise the dogs 20 out of engagement with the serrated table 125

portion 24 the handle 40 is lifted which raises all of the dogs 20 simultaneously out of engagement with the table. The dogs 20 are lifted in this position when it is desired to 5 fit the webbing strips 15 beneath the same in readiness to permit the free end of the strips 15 to be drawn between the dogs 20 and the table 23.

Directly in front of the table 23 I provide 10 a work table 41 which is connected to the forwardly extending members 42 carried and supported by the sides 11 and 12 so as to support the table 41 transversely between the sides 11 and 12. The top of the table 41, is 15 approximately in line with the top of the table 23 and when the webbing strips 15 are fed from the rolls 14 between the dogs 20 and the table 23 the webbing strips are drawn over the table 41 and extend from the same 20 to the piece of furniture such as F illustrated in Figure 1 of the drawings. The piece of furniture F illustrated in the drawings in Figure 1 is attached to any suitable supporting means such as the support G and is rigidly 25 connected thereto by a clamp 43 or any other suitable means so as to hold the same firmly on the support G. This permits my webbing machine A to be brought up to the article of furniture and the forward edge 44 30 of the table 41 positioned against the legs of the furniture or the side of the same. When the webbing machine A is in this position the webbing strips 15 are brought over to one side of a piece of furniture and firmly 35 nailed thereto. After the free ends of the webbing strips 15 are securely nailed to the piece of furniture F at the side 45, for example, the operator takes a hold of the portion 40 of the strips extending beneath the dogs 20 just back of the dogs and draws the same taut so that all of the strips 15 extending over the bottom of the furniture F are approximately 45 of the same tension. This operation is assisted by the dogs 20 which automatically release by pulling the webbing 15, while 50 stretching it by hand taut over the bottom of the furniture so that when the individual strips 15 are released the dogs automatically, by reason of their weight, at the free end 55 thereof, drop and are pulled by the engagement through the serrated surface 25 in a manner to lock the webbing between the serrated surface 24 and 25 and prevent it from slipping back toward the piece of furniture. 60 When all of the strips 15 are properly adjusted by hand to the desired tension over the bottom of the furniture, and which operation is very quickly accomplished by the operator, the arm 29 is lifted out of the locking notch 27 and by engaging the free end of the long handle 37, the operator presses 65 down on the same and rotates the table with the gripping dogs 20 in a manner to draw the web strips 15 very tight over the bottom of the furniture and stretch them evenly across

the same. In this operation as the lever 37 is pressed downward, the arm 29 having been released again after removal from the locking notch 27 is caused to engage with the ratchet teeth 31 and thus the operator can press the 70 handle down the desired amount and then when the handle is disengaged the arm 29 will act to lock the table member 23 in set rotated position with the webbing strips 15 drawn very tightly over the bottom of the furniture 75 F. The strips 15 are then nailed, for example 46, after which the strips 15 are cut off by running a knife through the groove 47 which is formed in the table portion 41 adjacent the edge 44. This groove is protected 80 by metal members on either side preventing the knife from cutting the groove and the operator can quickly cut the strips 15 off at the point after the knife is drawn through the groove 47. The free ends of the strips 15 85 are then folded back and nailed to the piece of furniture F so as to make a finished edge along the same.

This operation of my webbing machine provides means for stretching the webbing 90 very tightly over the bottom of the piece of furniture and provides a device which is quickly and easily operated, holding the webbing across the tables 23 and 41 in a manner so that the width of webbing designed to 95 come through the machine can be used, yet owing to the large number of individual gripping dogs 20 the webbing is gripped firmly without tearing it or injuring its surface so as to firmly hold it while being stretched and 100 to permit the stretching operation to be easily performed by the operator.

I provide an adjustable means for raising and lowering the operating and gripping mechanism E which includes an operating 105 wheel 50 adapted to operate the gear 51 which engages with the vertical extending rack 52 secured to each side 11 and 12 of the machine A and thus permit the sides 11 and 12 to be raised up and down on the base sides 53 which 110 extend upward from the base and which slidably support the gripping mechanism in relation to the base B. This permits the web stretcher to be adjusted to the height desired to bring it at the proper level with the bottom 115 of the furniture over which the webbing is to be stretched and attached.

The operation of the device is very rapid and a large number of pieces of furniture can be covered with webbing, being important 120 that the webbing is not at all injured in the stretching by the engagement of the dogs and the parts and so connected together that the operator can easily and more efficiently stretch the webbing across the bottom of the furniture. Thus I provide a web stretching machine which is adjustable and the parts of which operate automatically to simplify the construction and provide a practical web stretching device. It is important that the 125 130

rolls 14 of webbing be easily inserted in the machine so that they can be changed from time to time quickly. I have found the operation of my device to be very effective and it is to be preferred over other forms of web stretching machines which has been demonstrated by the large demand which I have had for these machines.

In accordance with the patent statutes I have described the principles of operation of my web stretching machine and I have illustrated a particular formation in the drawings. However I desire to have it understood that these illustrations are only suggestive of the construction of my device and that the invention can be carried out by other means and applied to uses other than those above set forth within the scope of the following claims:

20 I claim:

1. A web stretcher adapted to hold a series of webbing rolls, a table over which the webbing is adapted to extend in a manner so that the free end of the webbing can be attached to an article, self-acting gripping members adapted to engage the webbing and pinch the same against said table, means for releasing said members simultaneously and means for rotating said table with said gripping members to stretch the webbing very tight.

2. A web stretcher adapted to hold the series of webbing rolls, a web gripping table, means for rotatively supporting said table, a series of gripping members pivotally connected to and adapted to rotate with said table, a key means for limiting the rotative movement of said gripping members, said gripping members being adapted to co-act with the surface of said table to engage the strips of webbing passing thereover to permit the same to be individually engaged and pulled only sufficiently to equalize the strips of webbing in relation to each other, said gripping members operating automatically to prevent the webbing from moving in a backward direction after it has been drawn snug, means for rotating said table and gripping members collectively to stretch the strips of webbing and means for locking said table in the rotated position to hold the webbing stretched until it is attached and cut off.

JOHN A. FLOOD.
